US0D1049785S

(12) **United States Design Patent** (10) **Patent No.:** **US D1,049,785 S**
(45) **Date of Patent:** **** Nov. 5, 2024**

(54) **CONTAINER**

(71) Applicant: **ShenZhen YiHong Technology Co., LTD**, Guangdong (CN)

(72) Inventor: **Yi Dai**, GuangDong (CN)

(73) Assignee: **ShenZhen YiHong Technology CO., LTD**, ShenZhen (CN)

(**) Term: **15 Years**

(21) Appl. No.: **29/942,394**

(22) Filed: **May 15, 2024**

(51) LOC (14) Cl. **07-09**

(52) U.S. Cl.

USPC **D7/602; D7/629**

(58) **Field of Classification Search**

USPC D7/538, 589, 590, 601, 602, 608, 629,
D7/630, 701, 703; D9/414, 418, 425,
D9/430, 434, 435

CPC . A45C 11/20; A47F 1/035; B65D 2501/0081;
B65D 43/02; B65D 51/04; B65D 51/24

See application file for complete search history.

(57) **CLAIM**

The ornamental design for a container as shown and described.

DESCRIPTION

FIG. 1 is a top perspective view of a first embodiment of a container showing my new design;

FIG. 2 is a bottom perspective view thereof;

FIG. 3 is a left side view thereof;

FIG. 4 is a right side view thereof;

FIG. 5 is a back view thereof;

FIG. 6 is a front view thereof;

FIG. 7 is a top view thereof;

FIG. 8 is a bottom view thereof;

FIG. 9 is an exploded bottom perspective view thereof;

FIG. 10 is a top perspective view thereof, shown with the lid closed;

FIG. 11 is a top perspective view of a second embodiment of a container, showing my new design;

FIG. 12 is a bottom perspective view thereof;

FIG. 13 is a left side view thereof;

FIG. 14 is a right side view thereof;

FIG. 15 is a back view thereof;

FIG. 16 is a front view thereof;

FIG. 17 is a top view thereof;

FIG. 18 is a bottom view thereof; and,

FIG. 19 is a top perspective view thereof, shown with the lid closed.
